UNITED STATES PATENT OFFICE.

JAMES SAMUEL FOLEY, OF WEST BROMWICH, ENGLAND.

BICYCLE-BRAKE.

SPECIFICATION forming part of Letters Patent No. 592,745, dated October 26, 1897.

Application filed February 13, 1897. Serial No. 623,258. (No model.) Patented in England July 8, 1897, No. 15,093.

To all whom it may concern:

Be it known that I, JAMES SAMUEL FOLEY, engineer, a subject of the Queen of Great Britain, residing at High Street, West Bromwich, in the county of Stafford, England, have invented certain new and useful Improvements in Cycle-Brakes, of which the following is a specification, and for which I have obtained Letters Patent of Great Britain, dated 10 the 8th day of July, 1897, No. 15,093.

This invention relates to brakes principally for chain-driven velocipedes brought into operation (for retarding the progressive movement of a machine) through the medium of 15 the drive-chain by the act of back-pedaling; and it consists in providing at one end of the stationary spindle of a back wheel-hub or upon the end of the barrel of a bottom bracket or other suitable part of a cycle a fixed drum 20 or casing, against the inside of which a spring-band is expanded when the drive-chain, by reason of the rider back-pedaling, exerts a pull upon the chain-wheels in the contrary direction to that exerted in ordinary forward 25 driving.

When my invention is applied to the back hub of a cycle, the casing or drum is secured to the spindle end, as aforesaid, while the ends of the band-brake are respectively in connection with lugs or the like, one of which is carried on the outer face of a chain-wheel mounted so as to turn on the end of the hub, and the other is fixed upon the hub end itself, the arrangement being such that the ordinary 30 pull of the chain in forward driving brings the lugs on chain-wheel and hub together or into abutment, but when a rider sets up a back-pedaling action the chain tends to pull the chain-wheel around in the reverse direction, which separates the lugs and increases 35 the distance between the ends of the band-brake, whose diameter is thus slightly increased and its outer periphery brought into braking contact with the inner periphery of 40 the drum. Hence the motion of the machine is retarded.

Figure 1 of the accompanying drawings represents, partly in longitudinal vertical section and partly in elevation, a cycle-brake constructed according to my invention and applied to a back wheel-hub. The said view shows the positions which the parts of the

brake and the drive-chain indicated by the dotted lines take when the brake is in action. Fig. 2 is a like view as Fig. 1, but with the brake 55 off and the parts and chain shown in the position they normally occupy. Fig. 3 is a transverse vertical section upon the dotted line x , Fig. 2, of the chain-wheel end of a hub and the brake fitted thereto. Fig. 4 is an elevation 60 of Fig. 3, but with the casing, spindle, and brake-band removed. Fig. 5 is an elevation and a vertical section on the dotted line x^2 of the brake-band separately. Fig. 6 is a vertical section of the drum or casing separately, 65 and Fig. 7 is an inside elevation thereof. Fig. 8 represents an elevation of the brake in position upon a machine. Fig. 9 is an elevation and section of the chain-wheel separately, and Fig. 10 is a front elevation and 70 section of the ring separately.

The same letters of reference indicate corresponding parts in the several figures of the drawings.

a is the hub, having a chain-wheel b mounted 75 upon the head a' thereof. The head of the hub is provided with a peripheral collar or flange a^2 , against which the inner side of the chain-wheel rests. The outer end of the head a' is externally screw-threaded, as at a^3 , and 80 upon this threaded portion is screwed a collar or ring c , whereby the chain-wheel is confined in position between the collar or flange a^2 and the collar or ring c . The collar or ring is locked to the head of the hub by screws 85 c' . The chain-wheel is loosely mounted on the hub, so that it is susceptible of turning thereupon. The collar or ring c carries upon or has made fast to it a lug or stop c^2 , coming against the stop b^2 on the chain-wheel and 90 forming the thrust-bearing which rotates the driving-wheel on forward-pedaling.

d is a spring band-brake, the one end d' of which is made to abut an outwardly-projecting shoulder on lug or stop b^2 on the chain-wheel, 95 and the other end d^2 abuts an outwardly-projecting shoulder on the lug c^2 on the ring c , revolving with the hub, while the outer periphery d^3 is adapted to come into frictional contact with the opposed and inner surface 100 e' of the brake drum or casing e , the central boss e^2 of which is screwed upon the part f' of the stationary hub-spindle f , whose extreme outer ends f^2 are also threaded to take the

nuts g , which secure both the hub and the brake-casing to the slotted jaws h' of the back forks h of a machine.

e^3 is a stud or pin on the outside of the 5 brake-casing adapted to take into a hole h^2 in the said jaws h' as an additional security.

Assuming that a bicycle is being driven in the ordinary way through chain-gear by forward-pedaling, then the thrust-bearing lugs 10 b^2 and c^2 come in contact and the chain-wheel and hub rotate together; but supposing a rider wishes from any reason to apply the 15 brake he back-pedals, and the force thus exerted straightens the sagging or lower part 20 of the chain. This momentarily checks the rate of rotation of the chain-wheel, but has no immediate effect upon the speed at which the hub rotates, so that the hub runs on a little in advance of the wheel, which movement 25 separates the lugs to a slight degree and increases the distance between the ends of the band-brake, which is thus expanded against the inner periphery of the drum, setting up a braking action and retarding the forward motion of the machine to an extent proportional to the force exerted in back-pedaling and immediately the ordinary action 30 is resumed the parts resume their normal positions.

30 The application of my invention to the

front chain-wheel and other parts of cycles differs in no essential respect from its application to a back wheel, as herein described.

Having fully described my invention, what I desire to claim and secure by Letters Patent is—

The combination of a hub a having a head a' provided with a collar or flange a^2 and an externally-screw-threaded portion a^3 at its outer end, a chain-wheel b loosely mounted 40 on said hub, bearing against said collar or flange and having a lateral abutment b^2 , a collar or ring c screwed upon the outer end of the hub-head to retain the chain-wheel in position thereupon and having a lateral abutment c^2 , a fixed brake drum or casing e enclosing the collar or ring, and a spring brake-band following the contour of the drum or casing and having its ends engaged, respectively, with the said abutments on the collar 45 or ring and chain-wheel, substantially as and for the purposes described.

In testimony whereof I have hereunto set my hand in presence of two subscribing witnesses.

JAMES SAMUEL FOLEY.
